(57) **CLAIM**

The ornamental design for a safety shirt, as shown and described.

DESCRIPTION

FIG. 1 is a top front perspective view of a safety shirt, showing my new design;

FIG. 2 is a top rear perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof; and,

FIG. 8 is a bottom plan view thereof.

The evenly spaced broken lines shown in the drawings depict portions of the safety shirt that form no part of the claimed design.

The dash-dot-dash broken lines shown in the drawings denote the boundaries of the claim and form no part thereof. Portions of the safety shirt shown in the figures show stippling to include contrasting appearance, wherein a first stippling represents a first appearance (along a vertical stripe portion and along a first waistband portion) that contrasts with the non-stippled portions and a second stippling (along an outer boundary of the vertical stripe portion, a second waistband portion that is wider than and below the first waistband portion, and along a shoulder portion) that represents a second appearance contrasting with the non-stippled portions and the first appearance.
